CATHODE RAY OSCILLOGRAPH

Théodore Mathieu Vogel, Paris, and Paul Traverse, Montrouge, France, assignors to Compagnie pour la Fabrication des Compteurs et Matériel d'Usines A Gaz, Montrouge, Seine, France

Application November 2, 1936, Serial No. 108,742
In France November 15, 1935

7 Claims. (Cl. 250—141)

The present invention relates to improvements in the cathodes of cathode ray oscillographs of the cold cathode type.

In the apparatuses of this type hitherto known, it is, in fact, known that after a relatively short period of operation, for example of the order of several hours, the emission of electrified particles by the cathode ultimately brings about on its surface the formation of craters of the same form and nature as, but of smaller dimensions than, the craters of electric arcs. From this moment, the emission surface is impaired, and on the one hand the emission becomes irregular and much less intense, and on the other hand the concentration of the cathode beam (particularly in the space comprised between the cathode and the anode) becomes much more imperfect.

These drawbacks are particularly serious in non-detachable oscillographs such, for example, as those sealed like lamps, because they have the result of rendering such apparatuses practically useless after several hours of operation, and consequently oppose their development.

The object of the present invention is to obviate the aforesaid drawbacks by reducing the emissive portion of the cathode to a small fraction of its total surface and displacing this emissive portion over practically the entire extent of the surface of the cathode. The invention also comprises means of bringing about, on the surface of the cathode, the displacement of its emissive portion, these means being automatic and not necessitating any mechanical connection between the cathode and the exterior of the oscillograph. According to the invention, this continuous or intermittent displacement, which may be uniform or irregular, is produced by rotation, translatory movement, by oscillations or finally by helicoidal movement of the cathode or of one or more screens interposed between the cathode and the anode.

The accompanying drawing shows, simply by way of example, which is not limitative with regard to the forms and dimensions, a number of constructional forms of the invention.

In Figure 1, the cathode is constituted of a disc 1 disposed inside the cathode tube 2 and adapted to turn about a pin 3, for example under the action of the field of an induction member 4 disposed exteriorly of the tube 2. The anode 5 is eccentric with respect to the cathode 1, and between these two electrodes there is disposed a screen 6 having an aperture 7. It is obvious that in the device according to this figure all the successive points of an annular zone 8 of radius R, traced on the surface of the cathode 1, are successively utilised as emissive surfaces and that the aperture 7 of the screen 6 acts as a secondary cathode with respect to the anode.

In Figure 2, the cathode is constituted of a

cylinder 11 disposed inside the cathode tube 12 and adapted to be displaced by a helicoidal movement about a fixed pin 13 under the action of the field of an induction member 14 disposed exteriorly of the tube 12. The axis of the tube 12 is perpendicular to the pin 13. This tube encloses, on the one hand, the anode 15, and on the other hand the screen 16 having the aperture 17 therein. The cylinder forming the cathode 11 is connected with a member 18 having the screw required for bringing about its helicoidal displacement about the pin 13, and adapted to be driven by the couple of the induction member 14. In the device according to this figure, all the points of a spiral traced on the cylinder 11 are successively utilised as emissive surface. If the pith c of this spiral is sufficiently narrow, it will be seen that the device illustrated permits of successively utilizing all the zones of the lateral surface of the cylinder 11 as emissive surface. The aperture 17 of the screen 16 acts as a secondary cathode with respect to the anode.

Finally, in Figure 3, the cathode is constituted of a movable disc 21 driven by an inductor 24a, while, under the action of the inductor 24b, a screen 29 having a spiral shaped aperture 30 turns at a different speed. A second screen 26, which is fixed, has a slot 27 and is placed inside the tube 22, between the screen 29 and the anode 25. In order to ensure their driving by the inductors 24a and 24b, the cathode 21 and the screen 29 may be connected to two small cylinders (not shown).

As a result of the rotation of the cathode and of the spiral 30 in front of the fixed slot 27, the emissive portion of the surface of the cathode 21 is displaced along successive spirals traced thereon. For suitable relative values of the speeds of the cathode and of the screen 29, the successive spirals may be juxtaposed, and practically the entire surface of the cathode 21 is finally utilised as emissive surface. The slot 27 of the screen 26 acts as a secondary cathode with respect to the anode and a condenser coil, not shown, permits of obviating the drawbacks attending the displacement of the emissive surface along the entire length of this slot 27.

A similar result may be obtained by keeping the cathode 21 fixed and making the screens 26 and 29 turn at different speeds.

With a view to simplification, the above figures do not show the method of action of the induction members 4, 14 and 24 on the members which they are intended to drive. This driving may be effected by any other known means without departing from the scope of the present invention. For example, the inductor is excited by polyphase windings and produces a rotary field, the body to be driven then consisting in a simple solid member, in the form of a cylinder 60

or disc, or the inductor is excited with single-phase alternating current and the body to be driven provided with teeth along its periphery. The whole functions as a synchronous motor with 5 variable reluctance. However, in the latter case the addition of any of the known means for starting the movable members is provided.

In the same way, in the various forms of construction illustrated, the movable members are 10 driven with a continuous or uniform movement, but the improvements forming the subject of the present invention are not limited to this case. In particular, the invention covers the possibility of providing, instead of a rotation, a setting in 15 operation with an oscillatory movement of sufficient amplitude. To this end, for example, the induction member is constituted by a simple electromagnet excited with alternating current, while the member to be driven is connected with a 20 small permanent magnet.

In the device according to Figure 2, it is necessary for the helicoidal movement to be periodically reversed, for which purpose the invention provides for the periodical reversal of the connections of the induction member 14, this reversal being controlled, for example, by means of a synchronous motor feed by the same source as this inductor.

In a general manner, the scope of the invention 30 will be considered as covering any cathode the emissive portion of which is displaced on its own surface automatically and without mechanical connections with the exterior of the oscilloscope, irrespective of the means employed for obtaining 35 this displacement and irrespective of the nature of this displacement. The invention in particular provides for the possibility of the electrode which forms the cathode, or one or more screens interposed between the cathode and the 40 anode, being driven by electrostatic means, such as an electric fly, or simply oscillating, for example under the action of the force of gravity, its oscillatory movement being maintained or not by electrodynamic or electrostatic means.

45 The invention finally covers the possibility of the supplementary screen or screens provided above for forming the secondary cathode, being utilised at the same time to form a simple or compound electron lens, which may or may not 50 comprise the primary emissive cathode.

What we claim is:

1. A cathode ray tube, comprising a bulb, an anode and a disc-shaped cathode within said bulb, a pin arranged within the bulb parallel to the longitudinal axis of the tube and perpendicularly traversing the centre of said disc to 55 rotatably support the cathode, a screen between cathode and anode disposed parallel to said disc and having an aperture therein formed and 60 arranged to expose only a fraction of the cathode surface for the emission of the cathode beam, and means provided externally of said bulb for continuously turning said cathode disc about said pin, so as to regularly and continuously displace 65 the emitting spot along an annular line on the surface of said disc.

2. A cathode ray tube, comprising a bulb, an anode and a disc-shaped cathode within said bulb, a first disc-shaped screen rotatably 70 arranged in said bulb between anode and cathode parallel to and coaxial within the latter and hav-

ing a spiral slot therein, a second disc-shaped screen in said bulb between the anode and said first screen parallel to and coaxial with the same, and having a substantially radial slot therein, the slots in said screen exposing only a fraction of the 5 cathode surface for the emission of electrons, and means provided externally of said bulb for continuously imparting a rotary movement to said first screen, so as to regularly and continuously displace the emitting spot on the surface of 10 said cathode.

3. A cathode ray tube, as claimed in claim 2, in which said disc-shaped cathode is rotatably arranged in said bulb, and further means are provided externally of said bulb to continuously rotate 15 said cathode disc simultaneously with the rotation of said first screen and at a different speed.

4. A cathode ray tube, as claimed in claim 2, in which said second screen is rotatably arranged 20 in said bulb, and further means are provided externally of said bulb to continuously rotate said second screen simultaneously with the first one and at a different speed, the displacement of the emission spot on the cathode surface being defined by the relative displacement of the slots in 25 the two screens relative to each other and to the cathode.

5. A cathode ray tube, comprising a bulb, an anode and a disc-shaped cathode within said 30 bulb, a pin arranged within the bulb perpendicularly to said disc and coaxially with the same, a screen between cathode and anode disposed parallel to said disc and rotatably supported by the pin, an aperture in said screen to expose only a 35 fraction of the cathode surface for the emission of electrons, and means provided externally of said bulb for continuously turning said screen about said pin, so as to regularly and continuously displace the emitting spot along an annular 40 line on the surface of said disc.

6. A cathode ray tube, comprising a bulb, an anode and a disc-shaped cathode within said bulb, a pin arranged within the bulb parallel to the longitudinal axis of the tube and perpendicularly traversing the center of said disc to 45 rotatably support the cathode, a screen between cathode and anode disposed parallel to said disc and having an aperture therein formed and arranged to expose only a fraction of the cathode 50 surface for the emission of the cathode beam, and a stator including electric windings externally of said bulb for turning said rotor cathode disc about said pin, so as to displace the emitting 55 spot along an annular line on the surface of said disc.

7. A cathode ray tube, comprising a bulb, an anode and a disc-shaped cathode within said bulb, a pin arranged within the bulb perpendicularly to said disc and coaxially with the same, a screen between cathode and anode disposed parallel to said disc and rotatably supported by the pin, an aperture in said screen to expose only a 60 fraction of the cathode surface for the emission of electrons, and a stator provided with electric windings externally of said bulb for turning said screen about said pin so as to displace the emitting 65 spot along an annular line on the surface of said disc.
